UNITED STATES PATENT OFFICE.

THOMAS J. SANDS, OF AUBURN, RHODE ISLAND.

SLUG OR BUNCH CATCHER.

Application filed March 6, 1924. Serial No. 697,311.

This invention relates to an improved slug or bunch-catcher for clearing yarn, thread and other filaments from slugs, bunches and large knots or other irregularities. My improved device is particularly adapted for use with winding or other textile machines employed in transferring yarn from one container to another such as in winding the material from bobbins onto spools or cops. 10 My invention relates particularly to improvements in the structure and arrangement of the slug or bunch-catcher shown and described in my prior U. S. Letters Patent No. 1,012,449, dated December 19, 15 1911.

One object of the invention is to provide a device of the type specified which may be constructed from sheet-metal stampings at economical cost and with greater uniformity with respect to its manufacture in 20 large quantities.

Another object of the invention is to render the device proof against derangement and getting out of order, and also to insure 25 against wear or deterioration of its mechanism during long periods of use.

Another object of the invention is to provide improved means for adjusting the slug-catcher whereby a plurality of the units may be connected for accurate setting in uniform adjustment for the same size of yarn or 30 thread.

Another object of the invention is to provide improved thread or yarn-engaging means in the device which are less liable to chafe, abrade or otherwise injure the strand 35 passing through the slug-catcher.

Another object of the invention is to provide for greater convenience in cleaning the 40 device of slugs, bunches, lint and dirt gathered in the process of clearing or cleaning the yarn.

Further objects of the improvement are set forth in the following specification which 45 describes a preferred embodiment of the invention as illustrated by the accompanying drawings. In the drawings:

Fig. 1 is an elevation showing two of the 50 improved slug-catchers applied to use in series and showing the manner in which the thread or yarn draws therethrough, and also illustrating the means for adjusting several of the devices in unison;

Fig. 2 is a plan view of the device;

Fig. 3 is a plan view of the device in section taken on the line 3—3 of Fig. 1;

Fig. 4 is a sectional plan view of the frame of the device taken on the line 4—4 of Fig. 1 and showing the construction of the lower thread-guiding plate; 60

Fig. 5 is a detailed view of the blank from which the casing of the slug-catching element is constructed;

Fig. 6 is a detailed view of one of the toothed leaves or plate-members of the slug-catching element; and 65

Fig. 7 is a perspective view of the guard or yarn-shield for the slug-catching element of the device.

The invention in general consists in providing improved means for acting on a running yarn, thread or filament to detect and seize a slug, bunch or knot in the strand whereby the latter is broken so that the machine to which the material is delivering 70 will be arrested in operation and the operator given notice that the slug or other obstruction must be removed and the yarn pieced together again in the proper manner. To this end my improved device comprises, 75 essentially, a bearing-roller across which the yarn draws, and a cooperating slug-catcher or clamping-element arranged in such relation thereto that the yarn may normally draw freely between said elements; the 80 catcher being adapted to be engaged by a slug, bunch or knot to seize the latter against the roller whereby the yarn will be broken so that the slug or other enlargement may be removed. 85

Referring first to Fig. 1 of the drawings, I have here illustrated two of my improved slug-catchers arranged in series for operating on two individual strands, with means for coupling the two devices so that they 90 may be adjusted in unison from a distant point. The device is adapted for use in series on a gang or frame of winding machines with a slug-catcher for each winding-spindle, and in such case it is the common 95 practice to employ all of the winding heads for winding a certain size or count of yarn. Therefore, all of the devices are made adjustable in unison in accordance with the size of yarn being used. This practice eliminates the need for separate setting of each 100 of the devices and also insures uniform adjustment in accordance with requirements. 105

The single slug-catcher comprises, essentially, a main frame or support 2 which 110 is preferably stamped from sheet-metal and struck up in suitable dies to the form re-

quired. The frame 2 comprises a vertical back-plate 3, from the rearward side of which extends a loop-like arm 4 bent around to encompass a rod 5 on which the device 5 is supported. A screw 6 reaching down through the upper part of the arm 4 is threaded into the under part thereof and acts to clamp the arm on the rod 5 to hold the slug-catcher in fixed position on the machine. The rod 5 may be a part of the framework of the winding or other machine, or may be held in brackets projecting from the legs of the machine and extending in horizontal relation so that the slug-catchers may 10 be adjusted therewith to set them in the proper relation to their respective winding spindles. Projecting downwardly and rearwardly from the lower corner of the plate 2 is an ear 9 formed with a hole for receiving a horizontal sliding rod or bar 10 which is connected to adjust the contact-elements of the different devices. The contact- or bearing-roller 12, across which the yarn or other strand draws, is journaled on a stud 20 13 projecting from a pivoted arm 14. The arm 14 is pivoted at 15 to the upper part of the frame 2 at the rear of the plate 3, said plate being cut away at 16 to provide an opening through which the roller 12 projects. 25 At the lower end of the arm 14 is a slot 18 adapted to be engaged by a screw or pin 19 projecting from a collar 20 secured fast in place on the adjusting-rod 10. The screw 19 holds the collar 20 in place on the rod 10 and by releasing the screw the collar may 30 be adjusted therewith in order to set it in proper position for regulating the adjustment of the arm 14 and its roller 12.

Projecting forwardly from the bottom of the frame 2 is a slotted plate 21, see Fig. 4, having a flaring opening 22 leading into an eye 23 through which the thread or yarn y draws. A substantially triangular-shaped ear 24, cut away from the metal of the back-plate 3, is bent forwardly to overlie the thread-guiding plate 21 in spaced relation therewith, see Fig. 4. The ear 24 acts as a 40 yarn-retainer to hold the strand y in the guide-eye 23 after it has been threaded into place by drawing it in through the opening between the ear and the plate. At the top of the frame 2 is a forwardly-projecting plate 25, preferably cut away in skeleton structure to save weight, and having an inclined front edge which acts to lead the yarn into a guide-eye in the plate. Preferably, a porcelain or other vitreous eye 26 is set into the edge of the plate 25 in line with the eye 23 of the lower plate 21 so that the yarn y 45 is adapted to lead therethrough in a straight line in position to draw across the periphery of the contact-roller 12.

The upper right-hand portion of the frame 2 is formed with a rounded contour provided with a projecting portion 28 having 50 two spaced-apart ears 29 projecting forwardly therefrom. Pivoted between the ears 29 is a lever 30 having rearwardly extending ears 31 for receiving a pivot-pin 32 held in the ears 29. The lever 30 carries the slug- or bunch-catching element 35 which is pivoted thereto on a stud or pin 36 projecting rearwardly from its lower end, see Fig. 3. The lever 30 is adapted to be tilted or swung on its pivot 32 to withdraw the 55 slug-catching element forwardly away from the contact-roller 12 to provide for the removal of the slug, bunch or other obstruction caught between the roller and the catcher, and also for cleaning these elements of lint, specks, dirt and other collections gathered during the operation of the device. Normally, the catcher 35 is held in the position shown in Figs. 1, 2 and 3 by a spring 37 acting on the lever 30. The spring 37 is 60 coiled around the pivot-pin 32 with one end hooked across the end of one of the ears 31 on the lever 30 and its other end hooked across the edge of the back-plate 3. The spring 37 tends to hold the lever 30 in the position 65 shown in Figs. 2 and 3 with the end of the stud 36 bearing against the front face of the frame 2, and by pressing with the finger on the rounded portion 38 of the lever the latter may be swung outwardly for the purpose 70 above explained. Normally, the slug-catcher 35 hangs suspended below the roller 12 in the position illustrated at the left-hand in Fig. 1, a bent over ear or lug 39 at the lower end of the lever 30 contacting with the edge 75 of the catcher to maintain it in this position. When a slug or bunch occurs in the yarn it will catch on a projection at the upper edge of the member 35 to cause the latter to be raised to grip the yarn against the roller in the manner and for the purpose as 80 hereinafter more fully explained.

One feature of the present improvement consists in constructing the slug-catcher or clamping-element 35 in the manner as next 85 described. The catcher or clamping element 35 comprises a plurality of relatively thin leaves or plates 42 held in a sheath or casing 43 constructed from a sheet-metal blank of the form shown in detail in Fig. 5. It consists of two triangular-shaped wings 44 joined together by a relatively narrow strip or tab 45 and having ears or lugs 46 projecting from their outer straight edges. The wings 44 of the blank are bent to stand at 90 right-angles to the tab-portion 45, in opposite parallel relation to each other to adapt them to enclose the sides of the plates 42 held therebetween. The plates or leaves 42, shown in detail in Fig. 6, are of the same 95 general contour as the sides or wings of the enclosing sheath or casing 43 and are formed with sharp teeth or serrations on their outer curved edges. The plates are made right- and left-hand so that they may be assembled 100

with the teeth on adjacent plates staggered in relation to each other, as shown at the right in Fig. 1. That is to say, when the plates are placed side by side the teeth on any two adjacent plates, instead of aligning, will be staggered or offset so that the serrated face of the slug-catching element 35 will be completely covered with projections. In this way the teeth of any given row are spaced apart a distance equal to the thickness of the plates or leaves 42 so that the points of the teeth are exposed on all sides, see Fig. 3, to provide very fine sharp edges adapted to be caught by the slug, bunch, or other enlargement on the yarn. As before stated, the leaves 42 are held between the sides or wings 44 of the casing 43, and the connecting strip or tab 45 engages slots 47 cut through the lower edges of the leaves. The two sides of the casing 43 are bound together by means of a rivet 48 passing through suitable holes 49 in the leaves and holes 50 in the wings 44 of the casing 43. The stud 36 which pivots the catcher 35 to the lever 30 passes through suitable holes 51 in the wings 44 of the casing 43 and also through alining holes 52 in the leaves 42, a loose fit being provided so that the catcher will swing freely on its pivot. It is to be noted that the outer curved edges of the leaves 42 are eccentric to the axis on which the slug-catcher 35 pivots so that the points of the teeth are arranged progressively farther away from the pivot toward the bottom of the catcher. This provides that when the slug-catcher is raised by the action of the slug its toothed face will dog or cam against the periphery of the roll 12 to clamp the strand thereon in the manner and for the purpose as hereinafter more fully explained. It is further to be noted, as shown at the left in Fig. 1, that the curved edges of the wings or sides 44 of the casing 43 project forwardly beyond the teeth on the leaves 42 so that said edges will bear against the roll 12 when the clamping-element 35 engages therewith. This arrangement provides for protecting the points of the teeth from wear through contact with the hardened roll 12 when the clamping-element engages therewith.

The projections or lugs 46 on the sides or wings 44 of the casing 43 are bent over across the top, as shown in Figs. 1 and 2, to provide a socket for receiving a hardened plate or blade 53 which seats in suitable slots 54 formed by cutting away the upper edges of the leaves 42. The blade 53 has a sharpened edge projecting forwardly to a slight extent beyond the points of the upper teeth on the catcher and serving as the means for obstructing the passage of the slug or bunch between the catcher and the roller. Normally, with the catcher 35 in its depressed position, as illustrated at the left in Fig. 1, the teeth or serrated edges 40 of the leaves 42 are shielded from the passing yarn or thread by means of an arcuate or curved guard 55 supported on the frame 2 below the catcher. The guard 55 takes the form of a sheet-metal strip or ribbon which is slotted and opened out to provide portions 56 enclosing a pivot-pin or stud 57 riveted through the back-plate 3 of the frame 2. The rearward end of the guard 55 is curled upwardly and around to enclose a cylindrical weight 58 which is secured thereto by means of a pin or rivet 59. The weight 58 may be cut from a length of rod and is provided at its inner end with a projecting stud 60 received in a slotted opening 61 in the back-plate 3 of the frame 2. The engagement of the stud 60 with the ends of the slot 61 acts to limit the swinging movement of the guard 55 on its pivot. The forward curved arm 62 of the guard 55 is adapted to be swung upwardly with its edge in position just beneath the sharpened edge of the slug-catching blade 53. Through this arrangement the guard prevents the yarn from flying back and catching on the serrated face of the element 35, while being adapted to clear the edge of the plate 53 so that a slug or bunch will meet this edge to raise the element 35 to clamp the yarn against the roll 12 in the manner as hereinafter more fully explained. The forward end of the arm 62 of the guard 55 is punched out to provide two protuberances or swellings 63 on its face as shown in detail in Fig. 7. These protuberances form a channel for the yarn drawing across the face of the guard 55 and thus serve as a means for confining the strand to its course to prevent it from being laterally displaced or from whipping or drawing out of position between the catcher 35 and the roll 12.

Referring now to Fig. 1, the arm 14 which carries the roller 12 is adjusted in position to set the device with the proper spacing between the periphery of the roller and the forward edge of the blade 53 on the catcher 35. That is to say, the roller 12 is adjusted to bring its periphery a certain distance away from the edge of the blade 53 in accordance with the size of yarn to be operated upon, this adjustment being effected by sliding the rod or bar 10 to swing the arm 14. Any suitable means may be provided for longitudinally adjusting the bar or rod 10, and a convenient and simple arrangement for this purpose is shown at the right in Fig. 1. As here illustrated the rod 10 extends through a bearing 64 which may be a part of a bracket mounted on the supporting rod 5. The rod 10 is screw-threaded to receive nuts 65 abutting either side of the bearing 64. By releasing one of these nuts 65 and turning the other one the rod may be slid to the extent required to adjust the arms 14 of the whole series of slug-catchers,

and after the adjustment is made the nuts are tightened against the bearing to secure the rod in fixed position.

- The construction and arrangement of a preferred embodiment of my improved slug- or bunch-catcher having now been described its method of operation will next be explained: The devices are applied to position on the machine with their guiding-eyes 26 arranged below the tension-devices usually employed for tensioning the yarn before it passes to the winding mechanism. The rod 10 is then adjusted to set the rollers 12 in such position with relation to the slug-catchers 35 that the yarn or other strand *y* will draw between the periphery of the rollers and the edge of the slug-catching blades 53 with a slight clearance so as to avoid any undue chafing or abrasion of the material. As the yarn feeds to the machine it draws across the roller 12 which, being freely rotatable, will present no undue resistance to the draft of the strand. When, however, a slug, bunch or other enlargement in the yarn passes up through the lower guide-eye 23 it will encounter the sharp edge of the blade 53 and be obstructed thereby to cause the slug-catching element 35 to be bodily raised on its pivot 36 into the position shown at the right in Fig. 1; it being understood that normally the slug-catcher hangs in the position shown at the left in Fig. 1 with its teeth or projections 40 shielded from the yarn by the guard 55. When the catcher 35 is raised by the action of the slug or bunch, as above explained, its toothed portion will be brought up into position to engage the yarn to clamp the latter against the face of the roller 12, it being understood that the teeth or serrations on the catcher 35 are disposed in eccentric relation to its pivot so that the greater the lifting movement of the catcher the greater the clamping effect will be on the yarn. The result is that the slug or bunch will be firmly caught and bound between the roller 12 and the catcher 35 so that the passage of the yarn through the device will be halted or restrained and the strand broken. The breaking of the strand acts automatically through the usual stopping-devices applied to the winding or other machine to arrest the operation of said machine and the operator is notified thereby that piecing up is required.
- To clear the device previous to piecing up the thread and starting the machine again the operator presses on the lever 30 and swings the catcher 35 outwardly so that the end of the strand containing the bunch or slug may be withdrawn from the device, the slug or bunch broken out and the strand pieced again. After the yarn is pieced up the strand is drawn taut again to lead through the guide-eyes 23 and 26 and across the face of the roller 12, the slug-catcher 35

being meanwhile allowed to swing back into position, as shown at the left in Fig. 1. The machine is then ready to start again and the yarn will feed through the device without obstruction until another slug or bunch occurs to operate in the same manner to move the element 35 whereby the yarn is seized and broken to again stop the machine.

From the above it will be observed that my improvement provides a particularly simple and efficient device for the purpose specified, and one which may be manufactured most economically in quantity to provide for its use in large numbers at relatively small cost. As employed in series, a large number of the devices may be adjusted in unison and set with precision in accordance with the requirements dependent on the size of yarn being used. The improved slug-catcher is free from complication and proof against derangement and getting out of order, while also being adapted to resist wear or deterioration of its parts during long periods of use. It may be adjusted for operation on practically any size of yarn and may be set with such precision that properly tied knots are allowed to pass through the device without breaking the strand, while at the same time any undue enlargement such as a bunch or slug will cause the operation of the device to break the yarn to stop the machine. Furthermore, the device is adapted for most convenient adjustment or setting in multiple and also for ease of access and convenience in piecing up the yarn and cleaning away the accumulation of lint, loose ends, specks and motes gathered during the process of clearing the yarn.

What I claim and desire to secure by Letters Patent of the United States is:

1. In a slug- or bunch-catcher, the combination of a bearing-element across which the yarn draws, a movable slug-detecting element arranged in spaced relation with respect to the bearing-element to permit the yarn to draw therebetween, a pivoted lever on which one of said elements is mounted, and means to swing said lever to adjust the relative position of said elements to vary the space therebetween in accordance with the size of the yarn being operated upon.

2. In a slug- or bunch-catcher the combination of a bearing-element across which the yarn draws, a slug-detecting element arranged in spaced relation with respect to the bearing-element to permit the yarn to draw therebetween and adapted to be engaged by a slug or other enlargement on the yarn to operate to arrest its travel to break the strand, a pivoted lever, means to mount one of said elements on the lever adjacent its pivot, and means for rocking the lever on its pivot to effect a fine adjustment between the bearing-element and the slug-detecting element to vary the space therebetween in accordance

with the size of the yarn being operated upon.

3. In a device of the type specified, the combination of a frame, an arm pivoted on said frame, a bearing-roller rotatably mounted on the arm to adapt the yarn to draw freely across its periphery, a movable clamping-element adapted to be engaged by a slug or enlargement in the yarn to be moved thereby to clamp the yarn against the roller, and an adjusting element connected to the arm to move the latter to adjust the position of the roller in relation to the clamping element.

15. 4. In a device of the type specified, the combination of a bearing-element across which the yarn is adapted to draw, a clamping-element pivoted to swing into position to clamp the yarn against the bearing-element, a lever on which said clamping-element is pivoted, and means for mounting said lever to adapt it to be manually operated to swing the clamping-element laterally away from the bearing-element when it is required to withdraw the yarn from between said elements.

20. 5. In a device of the type specified, the combination of a frame, a bearing-element thereon across which the yarn draws, a lever pivoted to the frame to adapt it to swing laterally away therefrom, a clamping-element carried by said lever in opposite relation to the bearing-element and adapted to be engaged by a slug in the yarn to clamp the latter against the bearing-element, and means acting on the lever to normally maintain the clamping-element in line with the bearing-element.

25. 6. In a device of the type specified, the combination of a frame-member, a bearing-roller rotatively supported from said frame-member to adapt the yarn to draw across its periphery, a lever pivoted on the frame-member to adapt it to rock outwardly therefrom in the direction of the axis of the roller, an eccentric clamping-element carried by said lever to adapt it to be moved into position to dog against the face of the roller, and a spring for holding the lever in position with the clamping-element in opposite relation to the roller.

30. 7. In a device of the type specified, the combination of a sheet-metal frame having a back-plate formed with a guide-plate bent at right-angles thereto and provided with a thread-eye through which the yarn draws, an ear cut away from the back-plate of the frame and bent across the top of the guide-

35. plate in spaced relation thereto to provide an entrance for the yarn into the guide-eye while preventing its escape therefrom, a bearing-member supported from the frame to adapt the yarn to draw thereacross, and an eccentric clamping-element pivoted on the frame in opposite relation to the bearing-member to adapt it to be engaged by a slug in the yarn to be moved thereby to cause it to clamp the yarn against the bearing-member.

40. 8. In a device of the type specified, the combination of a bearing-member across which the yarn draws, a pivoted clamping-element having a serrated face adapted to be moved into position by a slug in the yarn to clamp the latter against the bearing-member, and a guard arranged in position to shield the serrated face of the clamping-element to normally prevent the yarn from engaging therewith, said shield formed with protuberances on its face between which the yarn is adapted to draw to maintain it in position in contact with the bearing-member.

45. 9. In a device of the type specified, the combination of a bearing-element across which the yarn draws, and a clamping-element having an eccentric face adapted to be carried into contact with the bearing-element to bind the yarn thereagainst, said clamping-element comprising a plurality of closely related segmental-shaped leaves with teeth on their curved edges, said teeth arranged in such relation as to be staggered across the face of the clamping-element when the leaves are assembled in overlying relation.

50. 10. In a clamping-element for slug-catchers or like devices, the combination of a plurality of relatively thin sheet-metal leaves of segmental shape having teeth on their curved edges, said leaves arranged in overlying relation with the teeth disposed in rows and the teeth of adjacent rows staggered in relation to each other to provide a plurality of serrations having the edges of the teeth exposed on all sides.

55. 11. A clamping-element for slug-catchers or like devices comprising a sheet-metal casing formed with opposite segmental wings and a relatively narrow strip connecting the same, a plurality of relatively thin sheet-metal leaves assembled between the wings of the casing and provided with serrations on their curved edges arranged in rows with the teeth in adjacent rows staggered to expose the edges of the teeth on all sides.

In testimony whereof I affix my signature.

THOMAS J. SANDS.
